UNITED STATES PATENT OFFICE.

ROBERT D. BRUCE, OF PITTSBURGH, PENNSYLVANIA.

AIR-NAVIGATING VESSEL.

1,175,595.

Specification of Letters Patent. Patented Mar. 14, 1916.

Application filed September 16, 1913, Serial No. 790,031. Renewed August 9, 1915. Serial No. 44,605.

To all whom it may concern:

Be it known that I, ROBERT D. BRUCE, a citizen of the United States, residing at Pittsburgh, in the county of Allegheny and State of Pennsylvania, have invented certain new and useful Improvements in Air-Navigating Vessels, of which the following is a specification.

My invention consists of an improvement 10 in air navigating vessels.

The vessel comprises, in its entirety, a round, cigar-shaped body or "fuselage" having a maximum diameter at about one third the distance from the front and tapering to a point at front and back; supporting 15 wings extending laterally from the body at each side, above its axial center, having front and rear receding edges meeting at the outer rear points and having upper convex and under concave surfaces; horizontal 20 and vertical stabilizing planes; horizontal and vertical rudders; a central fin; with suitable reinforcing frame work, operating gear, propeller, ground supporting elements, 25 etc. as shall be more fully hereinafter described and claimed.

One preferred form of the invention is shown in the accompanying drawings, in which:

30 Figure 1 is a plan view of the vessel embodying the invention. Fig. 2 is an enlarged cross section of the wing taken on the line II—II of Fig. 1. Fig. 3 is a detail plan view of the rear portion of the machine, back of section line IV—IV. Fig. 4 is an enlarged cross sectional view on the line IV—IV of Fig. 1. Fig. 5 is a detail view in elevation of the rear portion of the machine back of section line IV—IV. Fig. 6 is a 35 view of the machine in rear elevation. Fig. 7 is a view of the machine in side elevation. Fig. 8 is a view of the machine in front elevation. Fig. 9 is a plan view of a portion of the machine, embodying the main vessel and 40 wing structure, showing the wing construction in detail. Fig. 10 is a transverse sectional detail view, taken on the line X—X of Fig. 9. Fig. 11 is an enlarged cross sectional detail view, taken on the line XI—XI 45 of Fig. 9.

Referring to the main elements or members of the machine, A represents the "fuselage" or body; B, B, are the supporting wings; C, C, are the horizontal, and 50 C, C', are the vertical stabilizing planes;

D, D, are the horizontal, and D', D', are the vertical rudders, and E is the central fin.

The several main parts of the machine, together with the associated operating elements and other features of the invention, 60 are comprised in a structure designed to utilize the flowing lines and proportions of well-known natural bodies, as the bird and fish.

The several portions of the structure are 65 divided into a series of unit sections comprising the entire body longitudinally, as indicated by the lines u, u; v, v; w, w; x, x; y, y; and z, z,—Fig. 1. These several divisions or units divide the entire machine 70 longitudinally into five main sections, three of which constitute the body A, the remaining two comprising the tail portion.

The wings B as stated, extend laterally 75 of the body A, and are in depth about one-half of the length of the body, or equal to one and one-half of the main longitudinal units. The front edge of the wings join the body at its upper portion at the point b, substantially one-half of the first unit in 80 length backwardly from the front or nose of the body, and recede therefrom outwardly and backwardly in the form of a quarter circle having a radius described from the center b'.

The front curved cutting edge b² of the 85 wings, merges into the rear edge b³ at the point b⁴, terminating rearwardly on a transverse plane substantially coinciding with the rear terminal of the body on the line x, x. The radius of the rear edge b³ is defined 90 from the center b⁵, and said center, like center b', is located substantially in a line parallel with the axial center a, a, of the machine, and at each side thereof a distance 95 approximating the maximum diameter of the body, as indicated in Fig. 1.

The radius of the front edge of the wing is substantially two and one-half of the 100 divisional units, u, u, etc., and that of the rear edge about three and one-half of such units, giving good proportions to the wings as to curvature and spread laterally.

The upper surfaces of the wings are convex in the arc of a circle b⁶, b⁷, respectively, 105 of short and long radii, the lower surfaces being defined in a similar manner by radii forming arcs b⁸, b⁹, respectively, merging the upper and lower surfaces into the sharp front and rear edges b², b³, respectively, as 110

shown in Fig. 2. The cross sectional form of the wing as shown is maintained throughout its entire length.

The physical structure of the wing may be of any suitable material to insure strength, lightness and rigidity, as herein-after described. For the purpose of avoiding air pockets under the back portion of the wings along the body, small openings 10 b^{10} , between the wing and the body, are provided, extending forwardly from the rear edge toward the front about one third of the maximum longitudinal depth of the wing as indicated.

15 The "fuselage" or body A is round in form as shown, tapering toward the front point a' which is located materially above the axial center a, a , of about one-eighth the maximum diameter at its widest point. By 20 this form I provide a front-edge-displacing body area for the wings tending to rise upon the air or to climb upwardly in flight. The tapering lines of the body, together with the receding construction of the wings provides 25 for a minimum air resistance in forward travel and a corresponding maximum of a speed and sustaining power. Thus, with the wings placed as shown, spreading of the air is obtained which effects an operation 30 under the wings giving a maximum lifting power, the receding wing form reducing the head resistance by taking advantage of the viscosity of the air. Thus, when any given unit of air is acted upon, by the forward 35 part of the wing adjacent to the body, such unit of air, due to viscosity, tends to pull the next units outwardly along with it. By using a wing form having a quarter circle front as shown, receding outwardly and 40 backwardly toward the tip, the head resistance of the wings is very greatly reduced from the head resistance in any other form of construction of equal given area. This is because the greater part of the air 45 under the wings has been given a forward motion before being acted upon by the balance of the wing section following. The wing as thus formed in cross section gives a greater minus pressure on top and a 50 greater lifting power underneath with less head resistance, for the reasons stated.

The horizontal and vertical stabilizing planes C, C, and C', C', extend laterally and vertically over the rear portion of the body 55 as shown, to the point where the rudders D and D' are attached. The planes C and C' merge into the body at the point c , substantially a distance of two of the main units backwardly from its front and at about the same transverse plane as the juncture with the rear wing edges, and have concaved outer edges, merging smoothly into the body surface.

The planes C and C' are diminished in 60 depth at about their middle portion corre-

sponding with the rear terminal point of the body and are then widened backwardly to the points c^2 , substantially in the plane y, y , occupying in length about two of the five main longitudinal units. The purpose of 70 these planes is to stabilize the body in both directions, preventing vibration or tendency to sudden movement in any direction, while facilitating movement through the air longitudinally with a minimum resistance. 75

The rear or tail rudders D, D, and D', D', horizontally and vertically, correspond in normal position with that of the stabilizing planes C and C' and are pivotally hinged to a suitable transverse supporting frame d , 80 practically coinciding with the plane y, y . The rudders are capable of movement in either direction from their normal position, a maximum of approximately thirty degrees, as in Fig. 3. Planes C and C' are 85 likewise braced or stiffened by transverse frame c^2 , while longitudinal stiffening braces c^1 extend substantially for the full length of the planes from the body rearwardly to frame d , being preferably concaved in conformity with the edges of the planes themselves. These longitudinal stiffening braces are 90 preferably made in the form of tubes for the purpose of extending through them the manipulating wires d^2 for the rudder 95 vanes, the wires passing through the tubes forwardly to suitable actuating mechanism within the body A, and being connected at their rear terminals to the rudder vanes as at d^3 . These rudder vanes are of fish-tail 100 form, pivotally hinged at their inner ends to the supporting frame d , and are outwardly rounded, tapering back to the rear terminal points, and having inner compound curved edges, as shown. By this construction a maximum width is provided at the 105 front edges, the inner curved faces providing ample clearance for movement and manipulation of the several rudders, their long, narrow, tail-like form giving a more powerful action on the air than the short and wide forms in general use. By reason of this form as shown, the maximum pressure is obtained on the outer portions of the tail 110 rudders which gives a maximum balancing power to them when they are used to change the direction of the machine. 115

Each rudder tail piece is hinged independently, so that two can be used as one, or they may all be used at the same time in 120 opposite directions, providing for a torquing effect which may be used to maintain the lateral balance of the machine in lieu of warping the wings.

At the upper portion of the body A, it is 125 provided with a vertical upwardly projecting centrally arranged fin E, of about one-half the length of the body and a maximum depth of about one-quarter the body diameter, the fin merging into the body at front 130

and back, and rounded as shown. The purpose of this fin is to maintain lateral stability in the machine and to restore lateral balance as follows: Should one side of the machine drop too low, the operator may turn the nose of the machine in a direction away from the low side by means of the tail rudders, thereby causing the air to strike the side of the fin on the low side and thereby bring the machine again into balance by pulling up the low side.

The machine is provided at its front with a propeller F, mounted on the end of a shaft extending centrally through the nose of the machine at a' , geared with the driving motor inside the body. The body is provided with suitable running supports, as wheels G, mounted upon carrying frame g of any suitable construction and substantially below its maximum diameter. In the rear I also provide a downwardly and rearwardly extending trailing support H, having sufficient flexibility to cushion the machine on alighting and to provide for trailing action over the ground.

In Figs. 9, 10 and 11, I show in detailed illustration the construction of the wing members B, designed for the purpose of providing supporting strength and stability with corresponding lightness, for the purpose of providing the skeleton wing structures. As shown, the supporting body portion of the wings, extending laterally and rearwardly of the body A at each side, are formed of skeleton framework, consisting of front and back edge-forming frames 2 and 3 conforming in position to the front and rear edge-defining portions b^2 and b^3 , and intermediate similarly shaped and disposed box truss or spar members 4 and 5. All of said members extend bodily through the upper portion of the vessel body A, which may be formed of a series of cylindrical hoops or rings 6, to be covered with canvas or other suitable material.

The main strengthening members 4 and 5, which may be of any suitable material, are preferably of rectangular or box form in cross section, as shown in Fig. 11, preferably having front and rear reinforcing walls 6, 6, and 7, 7, respectively, the spar members as thus formed making abutting contact at the center of the body, as indicated at 8, and being rigidly joined together. The same is true of the front and rear edge members 2 and 3. The main spar members 4 and 5 have a maximum cross section at their inner portions, where they are rigidly connected together and to the main body, being thus continuous from end to end, and taper toward their extremities for lightness and strength.

The upper curved surfaces of the wings are defined by the upper strips 9 laid over the entire cross area of the frame structure,

radiating across the arc-shaped main supporting spar members 2, 4, 5, and 3, to which they are fixedly secured, as shown in Figs. 9 and 11, similar lower surface-defining and reinforcing strips 10 being inserted sectionally between the main lateral members, and defining therewith the lower concave area or surface of the wing structure. By this construction I provide continuous curved surfaces above and below, and supporting means somewhat closely adjacent for the attachment of a covering of canvas or other suitable material.

Between the upper strips 9 and lower strips 10, and extending between the several main lateral members, are vertical web members 11, constituting with these members, to which they are fixedly connected, I-beam constructions adapted to firmly brace the various strips against the attendant strains. These web members may, if desired, be hollowed out at intervals, as indicated at 12.

The entire wing structure, as thus made and connected with the body, forms with it a stiff supporting framework, obviating the necessity of any guy wires or supplemental supporting mechanism, providing for ample strength and carrying capacity, and avoiding the danger of failure of collapsing of the wings due to sudden strains. The wings, while thus being rigidly incorporated with the body or "fuselage", have a certain degree of elasticity at their outer portions, their tapering form providing for maximum efficiency in the air, greatest strength at their juncture with the upper portion of the body, independence of supplemental guy wire or other bracing, and providing a symmetrical and ample support for the body in flight.

The apparatus as a whole as thus constructed, is well adapted to maintain sustained flight and equilibrium in motion and to correct variations due to any of the known causes.

The wings as shown are slightly drooped downwardly over the upward portion of the body in the form of comparatively flat arcs, the terminals of the wings extending to a plane substantially co-extensive with the horizontal plane of the axial center, as indicated in Fig. 8.

The body A of the machine, while maintaining its general circular rounded form, tapering toward each end, may be provided with suitable entrance and exit openings for the aviator, and I have also indicated at a^2 window openings at each side of the body.

The construction and operation will be readily understood from the foregoing description. The advantages resulting from the stream line form of the body and wings, planes, rudders, and various other parts contribute to the speed and stability of the ma.

chine as a whole, providing for a minimum resistance in the direction of travel, immediate correction of undesirable variations, and a maximum efficiency by effecting prompt and continuous reactions in the air, due to the form of the machine and its parts.

While the general proportions of the machine as indicated above are designed for the best results and are substantially correct, it will be understood that I do not desire to be strictly limited to them as given, but that the principle of the invention may be carried out in an embodiment of the machine within reasonable limitations as to variation therefrom, and that all such changes or variations which are within the province of the designing engineer or skilled mechanic are to be considered as within the scope of the following claims.

What I claim is:—

1. A fluid navigating vessel having an elongated circular body provided with a continuously curved surface and laterally extended supporting wings drooping downwardly from the upper middle portion of the body curving backwardly therefrom, and terminating in the middle plane of the body.

2. A fluid navigating vessel having an elongated circular body provided with a continuously curved surface and laterally extended supporting wings having backwardly curved front and rear edges tapering toward a point opposite the rear terminal of the body, and vertically and laterally extending stabilizing planes extending rearwardly of the body.

3. A fluid navigating vessel having an elongated circular body provided with a continuously curved surface and laterally extended supporting wings having backwardly curved front and rear edges tapering toward a point opposite the rear terminal of the body, and vertically and laterally extending stabilizing planes merging into the body surface and extending rearwardly thereof.

4. A fluid navigating vessel having an elongated circular body provided with a continuously curved surface and laterally extended supporting wings having backwardly curved front and rear edges tapering toward a point opposite the rear terminal of the body, vertically and laterally extending stabilizing planes extending rearwardly of the body, and conformably arranged rudders pivotally connected at the rear of said planes.

5. A fluid navigating vessel having an elongated circular body provided with a continuously curved surface and laterally extended supporting wings having backwardly curved front and rear edges tapering toward a point opposite the rear terminal of the body, vertically and laterally extend-

ing stabilizing planes merging into and extending rearwardly of the body, and conformably arranged rudders having inner curved tapering edges and pivotally connected at the rear of said planes.

70

6. A fluid navigating vessel having an elongated circular body provided with a continuously curved surface and laterally extended supporting wings having backwardly curved front and rear edges tapering toward a point opposite the rear terminal of the body and in the central horizontal plane of the body.

75

7. A fluid navigating vessel having an elongated circular body provided with a continuously curved surface and laterally extended supporting wings extending from the upper forward portion of the body having backwardly and downwardly curved front and rear edges and upper convex and lower concave surfaces.

80

8. A fluid navigating vessel consisting of a round body tapered toward each end and having laterally extending wings curving outwardly and backwardly from its upper middle portion and also downwardly and terminating opposite the rear terminal of the body, rearwardly extending horizontal and vertical planes, and rearwardly extending rudders coinciding with said planes, substantially as set forth.

90

9. A fluid navigating vessel consisting of a round body tapered toward each end and having laterally extending wings curving outwardly and backwardly from its upper middle portion, rearwardly extending horizontal and vertical planes, rearwardly extending rudders coinciding with said planes, supporting framework therefor embodying longitudinal hollow brace members, and actuating connections for the rudders extending therethrough.

100

10. In a fluid navigating vessel, the combination of a cigar shaped body having a pointed nose and tail, laterally extending backwardly curving tapered and upwardly arched supporting wings extending laterally of the upper portion of the body and bowed downwardly at their tips to the middle plane thereof, stabilizing planes extending rearwardly of the body and merging thereinto, tapering rudders pivoted at the rear of said planes and forming extensions thereof, and a propeller, substantially as set forth.

110

11. In a fluid navigating vessel, the combination of a cigar shaped body having a pointed nose and tail, laterally extending backwardly curving tapered and upwardly arched supporting wings extending laterally of the upper portion of the body and curving downwardly to terminals opposite the middle plane of the body, stabilizing planes extending rearwardly of the body and merging thereinto, tapering rudders pivoted at the rear of said planes and forming ex-

115

120

125

130

tensions thereof, a propeller, and supporting and running gear, substantially as set forth.

12. The combination with the body, of a wing structure consisting of continuous tapered spar members and front and rear edge members extending through and connected with the body, all of said members being backwardly curved to a meeting point, substantially as set forth.

13. The combination with the body, of a wing structure consisting of continuous tapered spar members and front and rear edge members extending through and connected with the body, all of said members being backwardly and downwardly curved to a meeting point, substantially as set forth.

14. The combination with the body, of a wing structure consisting of continuous tapered spar members and front and rear edge members extending through and con-

nected with the body, all of said members 20 being backwardly curved to a meeting point and provided with reinforcing cross strips at top and bottom, substantially as set forth.

15. The combination with the body, of a wing structure consisting of continuous tapered spar members and front and rear edge members extending through and connected with the body, all of said members being backwardly curved to a meeting point and provided with reinforcing cross strips 30 at top and bottom, and intervening web members, substantially as set forth.

In testimony whereof I hereunto affix my signature in the presence of two witnesses.

ROBERT D. BRUCE.
